UNITED STATES PATENT OFFICE.

HARRY TRISTRAM BELLAMY, OF RIVER FOREST, AND WILLIAM HENRY GROVES, OF MELROSE PARK, ILLINOIS, ASSIGNEES TO WESTERN ELECTRIC COMPANY, INCORPORATED, OF NEW YORK, N. Y., A CORPORATION OF NEW YORK.

FURNACE.

Application filed April 18, 1924. Serial No. 707,343.

This invention relates to furnaces, and more particularly to an improved furnace or kiln for the maturing of ceramic wares. In some types of furnaces, particularly those of the vertical type, it is found that the temperature varies widely throughout various parts of the heating chamber. The reason for this is that oftentimes there is a greater heat dissipation from the top of the furnace than from the bottom, due to the fact that an opening must be left at the top of the furnace to permit the exit of combustion gases, and also due to the impracticability of insulating the top of the heating chamber as the bottom is usually insulated. The burners in this type of furnace are usually located at the bottom of the heating chamber which aggravates the condition described, but even when they are positioned along the sides, it is impossible to heat the upper area of the chamber as hot as the lower. On account of the wide range of temperature from the bottom to the top of such furnaces, which sometimes is as much as 150° F., it is very difficult to get satisfactory results in carbonizing materials, heat treating, and particularly, the firing of ceramic wares, where a uniform firing temperature is necessary.

The burners or heat projecting members of many of the present types of furnaces usually comprise a tubular piece of steel, wrought iron or cast iron. It is a well-known fact that such burners corrode badly, due to the high temperature of the furnace, particularly after the burner is shut off and the incoming gas no longer has a cooling effect.

An object of this invention is to insure a substantially uniform temperature throughout all parts of the heating chamber of a furnace.

Another object of this invention is to produce a furnace having an outlet for the gases of combustion positioned intermediate the heating zones.

Other objects of the present invention are to provide a furnace with improved heat projecting members and outlets for the gases of combustion.

A furnace constructed in accordance with one embodiment of the invention may comprise a cylindrical heating chamber, closed at the top and bottom, and provided with

a plurality of burners, some of which are positioned near the top of the heating chamber, and others near the bottom thereof, thus establishing spaced heating zones therein. A plurality of outlets for the gases of combustion may be provided, one of which is positioned in the wall of the heating chamber intermediate the top and bottom burners. The burners and also the flues are cast from a refractory including silicon carbide.

In the accompanying drawings,

Fig. 1 is a front elevation of a furnace embodying the features of this invention;

Fig. 2 is a horizontal section taken on the line 2—2 of Fig. 1 and looking in the direction indicated by the arrows, and

Fig. 3 is a detail sectional view through one of the burners.

Referring now to the drawings in detail, 10 represents a bed of fire brick or other refractory material upon which is mounted a cylindrical metal casing 11 supported by a plurality of clamping rings 12. The inner face of the cylindrical casing 11 is lined with a thick wall of fire brick or other refractory material 13, to form a cylindrical heating chamber 14. A suitable top 15 is provided to keep the heat within the heating chamber.

Extending tangentially through the casing 11 and lining 13 are a plurality of gas burners 16. A pair of these burners are positioned opposite each other near the top of the heating chamber 14, and a second pair of burners are positioned opposite each other near the bottom of said heating chamber. In this manner heating zones are provided at the top and bottom of the chamber. The gas burners 16 are cast from carborundum, and are suitably connected to gas pipes 17, as by a threaded collar 18. Each burner is provided with an air pipe 19 which comprises a suitable length of wrought iron tubing concentrically disposed within said burner.

In the preferred embodiment of the invention, the furnace is provided with three flues 20, one of which is positioned near the top of the heating chamber, another near the bottom thereof; and the third, intermediate the top and bottom burners. The flues 20 are cast from a refractory, preferably carborundum, because of its high heat resisting quality.

For a preferred method of casting the burners and flues from carborundum, reference is made to the pending application of Chas. C. Ramd, Serial No. 667,109, filed 5 October 8, 1923 on which Patent No. 1,564,274 issued. Cast carborundum burners and flues are of much advantage, especially for use in high temperature furnaces, because of the inherent high heat resisting 10 quality of carborundum, and its long life irrespective of the severe abuse to which it may be subjected. Also, by casting, the walls of the burners and flues may be made much thinner than by the molding method, which 15 enables them to better resist the abrupt changes of temperature to which they are sometimes subjected.

The articles to be fired are placed in a sagger 21, which is positioned in the center 20 of the heating chamber. Either of the burners 16 may be partially or completely shut off to regulate the heat within the chamber 14. When a uniform temperature is secured 25 throughout all parts of the heating chamber, the individual burner valves are undisturbed thereafter and the furnace may be shut off and turned on by means of a valve on the main feed line, not shown.

A furnace embodying the features of this 30 invention is particularly adapted for the maturing of ceramic wares because the temperature is maintained substantially uniform throughout all parts of the heating chamber, it never varying more than about 25° F.

35 What is claimed is:

1. In a furnace for ceramic materials, an 40 inclosed chamber, a plurality of burners for establishing a plurality of heated zones therein, and a plurality of flues for the gases of combustion positioned in and intermediate said heated zones.

2. In a furnace for ceramic materials, an 45 inclosed heating chamber and means for maintaining a uniform temperature in the

chamber, comprising a plurality of burners 45 projecting through the wall of said chamber in different zones, and a flue located in each zone.

3. In a furnace for ceramic materials, an 50 inclosed heating chamber and means for maintaining a uniform temperature in the chamber, comprising a plurality of burners projecting through the wall of said chamber located near the top and bottom thereof to establish a plurality of heated zones, and a 55 plurality of flues for the gases of combustion positioned in and intermediate said heated zones.

4. In a furnace for ceramic materials, a 60 vertically disposed heating chamber and means for maintaining a uniform temperature in the chamber, comprising a plurality of burners projecting into said chamber at different levels, and a plurality of flues leading from different levels of the heating 65 chamber.

5. In a furnace for ceramic materials, a 70 vertically disposed heating chamber and means for maintaining a uniform temperature in the chamber, comprising a plurality of burners, and a plurality of flues, said burners and flues being distributed throughout the heating chamber.

6. In a furnace for ceramic materials, a 75 vertically disposed heating chamber and means for maintaining a uniform temperature in the chamber, comprising a plurality of burners arranged in diametrically opposite pairs and at different levels of the heating chamber, and a plurality of flues spaced 80 in circumferential symmetry and at different levels of the heating chamber.

In witness whereof, we hereunto subscribe our names this fifth day of April, A. D. 1924.

HARRY TRISTRAM BELLAMY.
WILLIAM HENRY GROVES.
